UNITED STATES PATENT OFFICE.

CHARLES H. BOMBARDIE, OF SOUTH BEND, INDIANA, ASSIGNOR TO WIREBOUNDS PATENTS COMPANY, OF KITTERY, MAINE, A CORPORATION OF MAINE.

BOX.

1,329,332.

Specification of Letters Patent.

Patented Jan. 27, 1920.

Application filed February 20, 1917. Serial No. 149,924.

To all whom it may concern:

Be it known that I, CHARLES H. BOMBARDIE, a citizen of the United States, and resident of South Bend, in the county of St. Joseph 5 and State of Indiana, have invented an Improvement in Boxes, of which the following description, in connection with the accompanying drawings, is a specification, like characters on the drawings representing like 10 parts.

This invention relates to boxes and in its more specific aspect to that form of box known as a crate wherein the sides are made of spaced slats. I aim to provide a light 15 and strong crate with a removable lid and one which may be used as an open-top receptacle for storage purposes and which may be easily closed without the use of special tools to provide a strong shipping receptacle. 20 The crate herein disclosed is also one which may be shipped in the flat or knock-down condition and easily assembled in box form by the user.

My invention will be best understood by 25 reference to the following description of one illustrative embodiment thereof taken in connection with the accompanying drawings, wherein:

Figure 1 is a perspective view of a box 30 or crate with the cover removed;

Fig. 2 is a similar view of the same with the cover secured in position;

Fig. 3 is a perspective view of the blank 35 from which the side and bottom sections of the box are made;

Fig. 4 is a perspective view of one of the end sections;

Fig. 5 is a view of one of the lower corners 40 of the box partly broken away; and

Fig. 6 is a view of one of the upper corners.

Referring particularly to Fig. 3, I construct my box or crate of three sections 1, 3 and 5 comprising cleats 7, 9 and 11 respectively and side material, here shown as 45 spaced slats 13 so that the completed box is of the kind known as a crate.

The three sections 1, 3 and 5 are assembled in the flat, as shown, and are connected in co-operative foldable relationship by binding 50 wires 15 secured by staples straddling the same and extending through the side material and into the cleats and, if desired, by other binding wires 17 stapled to the side material and disposed between the cleats.

55 The parts are so arranged that when the

side sections 1 and 5 are folded up the cleats 7 and 11 thereof will mate with the cleats 9 of the bottom section 3, in the present instance forming mortise and tenon joints therewith, and the wires 15 and 17 will be 60 tensioned over the edges of the box. The principle will be recognized as that of the well-known "wirebound" type of box.

When the blank as shown in Fig. 3 is folded up as described, two end sections 19, 65 which may be of the form shown in Fig. 4, are assembled therewith. Each end section 19 may comprise a cleat 21 corresponding to the fourth or cover side of the box and adapted to mate with the cleats 7 and 11 and co-operating therewith to outline or frame the box ends, wall-forming material preferably in the form of spaced slats 23 and suitable means for retaining the box end in position at a location remote from the fourth side. 70 Such means is here shown as an additional cleat or batten 25 designed to interlock with the cleats 7 and 11. This interlocking may be conveniently provided for as shown in Fig. 5, by providing the cleat or batten 25 75 with suitable tenons and by making the mortises of cleats 7 and 11 of such size as to receive the tenons both of the cleat 9 and of the cleat 25. It is apparent that the side section 19 may be placed in position with 80 the cleat 25 on top of the cleat 9 and the side sections 1 and 5 fold up above them to form a complete five-sided box with an open top.

In order to secure the box parts in position so that the box may be used without a 85 cover as a receptacle, I preferably provide suitable lengths of wire 27 corresponding to the fourth side of the box and having provision for detachably securing the same to the wires 15 surrounding the side and bottom sections at the ends of the box so as to 90 form continuous bindings encircling the box ends. Preferably these wires 27 are secured in position on cleats 21 by stapling, as clearly 95 shown in Fig. 1.

100 While the wires 27 and 15 may be secured together in any desirable way, I have here shown them as having ends formed into co-operative portions of the so-called "Tyloop" fasteners. These fasteners are 105 formed by turning back the end of the wire on the standing part and intertwisting it therewith. As shown in Fig. 6, a loop or bight 29 will be provided on the end of one wire through which the twisted part of a co- 110

operating end may be reeved and bent over in the form of a hook 31. Preferably the parts are so proportioned that the throat of the hook 31 where it engages the loop or bight 29 is made of a double thickness of stranded wire, that is, by the end inter-twisted with the standing part. Such a fastening is secure and may be opened and closed many times without the use of special 10 tools and without impairing the integrity of the wire, but while this form of fastening is applicable for our purpose, we are by no means limited to its use.

The open-top box formed as described is 15 light and yet exceedingly strong, since both the ends are completely outlined by substantial cleats and since it is encircled by the wire bindings formed by the coöperation of wires 27 with wires 15. These bindings resist 20 diagonal strain on the box by tightening around it because of their universally flexible nature and the box although it has no top possesses the advantages hitherto associated solely with the wirebound box of 25 the type shown in Reissue Letters Patent to Inwood and Lavenberg No. 12,725 dated Nov. 26, 1907, wherein a closed receptacle is provided having universally flexible ligatures encircling the same and tensioned over 30 the edges thereof to permit flexibility under longitudinal strain while resisting undue distortion.

To close the box to form a shipping receptacle a cover section 33 is provided. 35 This cover 33 may be formed of suitable side material and is preferably adapted to rest upon the cleats 21 of the end sections. I have here shown it as comprising suitably spaced slats connected together by binding 40 wires. The binding wires here shown include wires 35 corresponding to the wires 17 of the body part of the box and preferably wires 37 corresponding to the wires 15. The end portions of all these wires have suitable 45 provision for detachably securing them to the body wires, herein shown as portions of "Tyloop" fasteners.

When it is desired to close the box the cover is placed in position and the wires 35 50 and 17 joined. The hooks 31 of the wires 15 may be straightened and engaged with the loops of wires 37 and bent down. In the embodiment of the invention shown the wire 27 is secured to the cleat 21 and a separate wire 37 is provided which is permanently secured to the cover 33 for completing the binding about the box end when the lid or cover is in place. Preferably I have the hook 31 reeved through both wires 27 55 and 37, as clearly shown in Fig. 6. The closed box shown in Fig. 2 is a firm and substantial receptacle adapted to withstand the stresses of shipment.

It will be noted that the box herein shown 60 may take as it were three forms. First, the

knock-down or shook form wherein the blank shown in Fig. 3, two end pieces shown in Fig. 4 and a lid herein appearing detached from the box in Fig. 1 are provided, all of which parts may be readily stored in 70 small space. Second, the open-top type of box utilized as a storage receptacle or as a handling receptacle for short distances, the lid 33 being kept separate and conveniently stored. Third, the closed shipping receptacle shown in Fig. 2. Attention is called 75 to the fact that no particular tools or technical skill is required to construct either of the latter two from the blank materials of the first and that the cover section may be 80 removed from the closed shipping receptacle and stored away or reused when needed again and that either of the boxes proper may be readily unfolded into the component elements of the shook or reassembled therefrom 85 with ease. Because of these characteristics the box is very desirable especially when there is combined therewith the utility of the "wirebound" principle wherein light and cheap material may be used for the side 90 walls of the box and yet great strength obtained by the provision of wire bindings joined with the side material and cleats in such manner that they by their tensile resistance resist the breaking strain put upon 95 the box.

Having thus fully explained the structure of the particular embodiment of my invention disclosed in the accompanying drawing, I should point out that the exact details 100 shown and to which I have specifically referred are not essential but that they could be changed considerably without departing from the spirit of my invention.

I claim:—

1. A box comprising relatively foldable side and bottom sections having coöperating reinforcing cleats, end sections having cleats corresponding to the fourth side of the box and constructed to interlock with the cleats of the side sections in a manner to prevent inward and outward displacement of said end sections, and readily manipulatable separable fastening means carried by said end sections and the side sections 110 to hold the parts in open top box form.

2. A box comprising relatively foldable side and bottom sections having coöperating reinforcing cleats, end sections having reinforcing members adapted to interlock with the cleats of other sections, a lid section, the side sections being provided with portions of readily manipulatable separable fasteners and said end sections and said lid having portions of fasteners to coöperate with the 115 portions on said side sections.

3. A box comprising three relatively foldable side sections secured together by binding wires and each comprising side material and reinforcing cleats, end sections having 120

105

110

115

120

125

- cleats corresponding to the fourth side of the box and having provision for interlocking with the cleats of other sections at locations remote from said side, and wires corresponding to the fourth side of the box having provision for detachable engagement with the wires of the box body.
4. A box comprising three relatively foldable side sections secured together by binding wires and each comprising side material and reinforcing cleats, end sections having cleats corresponding to the fourth side of the box and having provision for interlocking with the cleats of other sections at locations remote from said side, and wires secured to the cleats of said end sections and having provision for detachable engagement with the wires of the box body.
5. A box comprising three relatively foldable side sections secured together by binding wires and each comprising side material and reinforcing cleats, end sections having cleats corresponding to the fourth side of the box and having provision for interlocking with the cleats of other sections at locations remote from said side, a lid adapted to rest on the cleats of said end sections, wires secured to said end sections and to said lid both having provision for detachable engagement with the wires of the box body.
6. A box comprising three relatively foldable side sections secured together by binding wires and each comprising side material and reinforcing cleats, end sections having cleats corresponding to the fourth side of the box and having provision for interlocking with the cleats of other sections at locations remote from said side, a lid adapted to rest on the cleats of said end sections, wires secured to the end sections, and wires secured to said lid having provision for detachably securing the wires of the box body thereto, said latter wires being formed for alternative engagement with the wires of the end sections or with both the wires of the end sections and lid.
7. A box comprising relatively foldable side and bottom sections having coöperating cleats, wires connecting said sections secured to said cleats, end sections each having a cleat corresponding to the fourth side of the box and having provision for interlocking with the cleats of other sections at locations remote from said side, and means carried by the cleats of said end sections to be detachably secured to the said wires to hold the parts in box form.
8. A box comprising relatively foldable side and bottom sections having coöperating cleats, wires connecting said sections secured to said cleats, end sections each having a cleat corresponding to the fourth side of the box and having provision for interlocking with the cleats of other sections at locations remote from said side, means carried by the cleats of said end sections to be detachably secured to the said wires to hold the parts in box form.
9. A box comprising relatively foldable side and bottom sections having coöperating cleats, wires connecting said sections secured to said cleats, end sections each having a cleat corresponding to the fourth side of the box and having provision for interlocking with the cleats of other sections at locations remote from said side, wires carried by the cleats of said end sections, said wires and the wires before mentioned of the box body being formed into coöperating hook-and-eye fasteners whereby the parts may be detachably secured together in box form.
10. A box comprising relatively foldable side and bottom sections, end sections embraced thereby, and a separate lid, the side sections being provided with portions of readily manipulatable separable fasteners, and portions of fasteners on said end sections and lid both adapted to coöperate with those of the side sections.
11. A box comprising relatively foldable side, bottom and end sections having reinforcing cleats outlining the box ends, and flexible binders including portions attached to the side and bottom sections and coöperative portions attached to the end sections, and readily manipulatable separable fastening means uniting said portions at the corners.
12. A box comprising relatively foldable side, bottom and end sections having reinforcing cleats outlining the box ends, and flexible binders including portions attached to the side and bottom sections and coöperative portions attached to the end sections, and readily manipulatable separable fastening means uniting said portions at the corners, and a separate lid also provided with portions of binding means corresponding to those of the end sections and adapted to coöperate with those attached to the side and bottom sections.
13. A box comprising relatively foldable side and bottom sections, binders flexibly uniting them, interlocked end sections, the several sections having reinforcing cleats outlining the box ends, and portions of binding means attached to the end sections and lid, the ends of said binding means and of the binding means for the side sections being provided with readily manipulatable separable fastening means, said fastening means of the side sections being common to those of the end sections and lid.
14. A box comprising relatively foldable side and bottom sections, said side sections having reinforcing cleats, end sections hav-

ing reinforcing members adapted to interlock with the cleats of side sections, to lock said end sections against movement inwardly or outwardly of the body of the box, 5 and readily manipulatable separable fastening means carried by said end sections and the side sections to hold the parts in box form.

15. A box comprising relatively foldable 10 side and bottom sections having coöperating reinforcing cleats, end sections having reinforcing members adapted to interlock with the cleats of other sections, to lock said end sections against movement inwardly or outwardly of the body of the box, a lid section, 15 the side sections being provided with portions of readily manipulatable separable fasteners and said end sections and said lid having portions of fasteners both to coöperate 20 with the portions on said side sections.

16. A wirebound box comprising relatively foldable side and bottom sections having coöperating end cleats and connected together by binding wires, removable end sections 25 interlocking with the cleats of the side sections in a manner to prevent inward and outward displacement of said end sections, and readily-manipulatable separable fastening means securing the end sections and side 30 sections together to hold the parts in open-top box form.

17. A wirebound box comprising relatively foldable side and bottom sections having coöperating end cleats and connected together by binding wires, end sections having 35 cleats adjacent to the open side of the box, and readily-manipulatable separable fastening means securing the side sections to the last mentioned cleats.

40 18. A wirebound box having separable end sections and a separate lid, portions of separable fastening means on the end sections and lid, and portions of separable fastening means on the side sections for coöperation 45 with both of the fastening means on the end sections and lid.

19. A wirebound box comprising relatively foldable side and bottom sections having coöperating end cleats and connected together by binding wires, end sections having 50

cleats adjacent the fourth open side of the box, and separate wires independent of a lid corresponding to the fourth side of the box having provision for detachable engagement with the wires of the box body. 55

20. A wirebound box comprising cleats outlining the ends of the box; side material for three sides of the box; the cleats corresponding to the fourth side being unattached to side material; wire bindings extending around the cleats at the ends of the box; and a separate lid having wires corresponding to and adapted to be secured to the said wire bindings which extend around the cleats. 60

21. A wirebound box comprising relatively foldable side and bottom sections connected by wire bindings; end sections embraced thereby; and separable wires uniting said wire bindings across the top of the box 70 independently of a lid. 65

22. A wirebound box comprising relatively foldable side and bottom sections connected by binding wires; separable end sections embraced thereby; and separable fastening means carried by said end sections for connection with said binding wires. 75

23. A wirebound box comprising relatively foldable side and bottom sections connected by binding wires; cleats on said side 80 sections; separable end sections; transverse wires carried by said end sections; and fastening means for connecting said cleats with said transverse wires.

24. A wirebound box comprising relatively foldable side and bottom sections connected by binding wires; cleats on said side sections; end sections having cleats coöperating with those of the side sections; and wires on said end sections separably uniting 90 the binding wires on the side sections. 85

25. A wirebound box comprising side material and cleats for three sides of the box; cleats for the fourth side unattached to side material; and wire bindings around the 95 cleats at the box ends, including separable portions corresponding to the fourth cleats.

In testimony whereof I have signed my name to this specification.

CHARLES H. BOMBARDIE.
